UNITED STATES PATENT OFFICE.

FRANK DI BELLA, OF NEW YORK, N. Y.

PERMUTATION LOCK.

1,413,393.

Specification of Letters Patent. Patented Apr. 18, 1922.

Application filed May 9, 1921. Serial No. 468,002.

To all whom it may concern:

Be it known that I, FRANK DI BELLA, a citizen of the United States, residing at New York, in the county of New York and State of New York, have invented certain new and useful Improvements in Permutation Locks; and I do declare the following to be a full, clear, and exact description of the invention, such as will enable others skilled in the art to which it appertains to make and use the same.

This invention relates to an improved permutation lock and one object of the invention is to provide a permutation lock having improved tumbler mechanism and having an improved bolt and operating means for the bolt actuated through the medium of a shaft associated with the tumbler mechanism.

Another object of the invention is to so construct this lock that the shaft for imparting movement to the bolt may be rotated and move with it a core of the bolt when the main body of the bolt is locked against movement.

Another object of the invention is to provide the bolt with improved means for guiding its sliding movement, this means consisting of arms one of which may be engaged to releasably lock the bolt against sliding movement.

Another object of the invention is to provide an improved type of locking block for preventing sliding movement of the bolt, the locking block being yieldably held in engagement with the tumblers of the permutation mechanism and moving to a position permitting sliding of the bolt when the tumblers are in the proper position.

Another object of the invention is to provide improved means for connecting an eccentric wheel or disk with the actuating shaft, the disk when in use being positioned within a band loosely connected with the core of the bolt.

Another object of the invention is to provide an improved means for mounting the tumblers of the permutation mechanism within the housing of the lock and to also provide improved operating means for the tumblers.

Another object of the invention is to provide an improved socket for use in connec-

tion with the lock, the socket being so constructed that a sliding plate forming part 55 of the socket may be moved to an inoperative position and releasably held in the inoperative position against the action of a spring normally holding the plate in an operative position.

Another object of the invention is to provide an improved latch which may be permitted to engage the sliding plate and which may be moved in a releasing position to permit closing of the plate when the door is 65 closed and the latch is engaged by the bolt extended in the operative position.

Another object of the invention is to so construct this socket that under ordinary circumstances closing of the door with the 70 bolt extended will not serve to release the sliding plate of the socket.

Another object of the invention is to so construct this lock that while it may be easily set by an authorized person, it will 75 be difficult for an unauthorized person to set the combination and open the lock.

This invention is illustrated in the accompanying drawings, wherein:

Figure 1 is a view showing the lock in 80 elevation with the cover plate of the body portion of the lock removed.

Figure 2 is a longitudinal sectional view through the lock taken along the line 2—2 of Fig. 1, with the cover plate in place.

Figure 3 is a view in elevation looking at the operating parts of the lock.

Figure 4 is a view similar to Fig. 1 showing the door jamb socket in longitudinal section.

Figure 5 is a view showing the door jamb socket in elevation with the sliding plate moved to an open position.

Figure 6 is a longitudinal sectional view taken along the line 6—6 of Fig. 5, with the 95 sliding plate locked in an open position and the bolt-operated latch inoperative.

Figure 7 is a view similar to Fig. 6 showing the bolt-operated latch in an operative position.

Figure 8 is a transverse sectional view through the lock taken along the line 8—8 of Fig. 1.

Figure 9 is a transverse sectional view taken along the line 9—9 of Fig. 1.

Figure 10 is a perspective view of the

latching block which engages the permutation tumblers.

Figure 11 is a group view showing in perspective the permutation mechanism.

5 Figure 12 is a perspective view of one of the clamps which serve to rotatably mount the permutation tumblers.

10 Figure 13 is a group view showing in perspective the elements of the locking bolt 10 and actuating disk which fits into a collar of the bolt mechanism.

15 Figure 14 is a perspective view of a clamp which holds the tumbler-engaging bolt slidably in place and also assists in controlling movement of one of the arms of the bolt mechanism.

20 This improved permutation lock is provided with a housing 1 which will be secured to the door 2 by securing screws 3 and is provided with a tubular neck extension 4 which extends through the door as shown in Fig. 2. A cover plate 5 is provided for this housing 1 and is removably held in place by securing screws which pass 25 through openings formed in the cover and are screwed into threaded sockets 6 and 7 formed in the housing. The cover plate 5 is provided with a socket extension 8 which will be positioned in alinement with the neck extension 4 when the cover plate is 30 connected with the housing 1 and will receive one end portion of the hollow shaft 9 upon the outer end of which will be secured a head 10 by means of which the 35 shaft may be easily rotated.

The hollow shaft 9 forms a portion of the permutation mechanism disclosed in Fig. 11 and when in place has its head 10 seated in the head 11 of the dial 12. This 40 dial 12 fits into the cup 13 which is secured to the outer face of the door by securing screws 14 covered by the dial 12. A sleeve 15 extends inwardly from this dial into the neck 4 of the housing 1 and is provided at 45 its inner end with spaced arms 16 between which will fit the spaced arms 17 which extend from the hollow neck 18 of the permutation tumbler 19. It will thus be seen that when the arms 16 are positioned 50 between the arms 17, there will be provided a hollow shaft between the dial 12 and the tumbler 19. Other tumblers 20 and 21 fit about the hollow shaft between the tumbler 19 and dial 12 and will be positioned in the 55 housing 1 and be rotatably mounted and held in the proper spaced relation by means of clamps 22 one of which is shown in perspective in Fig. 12. These clamps are pivotally mounted by fasteners 23 which 60 pass through the openings 24 and after being swung into the clamping position shown in Figs. 1 and 2 to position the tumblers 19, 20 and 21 in the seats 25, 26 and 27, will 65 be releasably secured by screws or other removable fasteners 28 which will pass

through the openings 29. Each of the tumbler disks is provided with a notch or recess 30 upon its peripheral edge face and each is further provided with a plurality of threaded openings 31 so that abutment 70 screws 32 may be screwed into selected openings 31 and thus permit the combination of the permutation lock to be changed when desired.

The bolt 33 is slidably mounted in the 75 housing for moving outwardly through a cut out in the end wall of the housing between the blocks 34 which in addition to serving as guides for the bolt, provide supports so that a cross bridge 35 may be secured across the bolt and held in place by securing screws which extend through openings in the bridge and are screwed into threaded openings 34' formed in the blocks 34. By this arrangement, the bolt 33 will 80 be slidably held in place and may not move out of the proper position. This bolt 33 is hollow thus providing a chamber 36 in which a core 37 will be slidably mounted and yieldably held against sliding movement by means of a clutch consisting of a spring 38 positioned in a passage 39 of the core and gripping balls 40 pressed outwardly by the spring 38 and thus held in firm engagement with the walls of the 85 pocket. An opening 35' is formed in the bridge for registering with an opening 41 in the bolt and permitting the bolt to be securely locked by means of latch mechanism to be hereinafter described. This bolt 100 33 is provided with side arms 42 and 43, one of which is provided with a longitudinally extending slot 44 to receive a securing screw 45 and the second of which is provided with a depending finger 46 for fitting 105 into a groove 47' formed in a rib 47 upon the bottom of the housing. When the lock is in use, it is desired to have the bolt slide longitudinally and in order to do so, there has been provided an eccentric ring 48 which is mounted upon the tubular shaft 9 within a circular band 49 from which extends an ear 49' loosely connected with the core 37. A pin 51 extends through openings formed in the neck 52 of the ring and through a set of openings in the hollow shaft 9 so that when the shaft is turned, the eccentric will be moved and thus through the medium of the band 48 sliding movement imparted to the core. Under 110 normal circumstances, the core will be frictionally held against movement in the pocket and therefore the bolt 33 will move with the core but when the bolt is held against sliding movement, the core may 115 slide in the pocket and thus prevent breakage of the lock. In order to prevent the pin from being accidentally caused to slip out of the openings of the neck 52 and the shaft 9, the pin has been provided with an 120 125 130

eye 53 through which a securing screw 54 will be passed and screwed into a threaded opening formed in the ring 48. It will thus be seen that the eccentric ring 48 will be 5 securely but releasably locked upon the shaft 9.

In order to permit the bolt to be locked against sliding movement when desired, there has been provided an abutment block 10 55 which is positioned between the side wall of the housing and the permutation tumblers and extends between the end portions of the clamps 22 so that the block will be held in engagement with the edges of the tumbler disk by means of a spring 56 which engages the wall of the housing and the outer end of the block 55. This block is provided with a transversely extending passage 57 through which the arm 43 of the bolt may 20 pass and the block is slidably held in the proper position by means of a housing or clamping bracket 58 which is secured to the bottom of the housing 1 by fasteners which pass through the side wings 59 of 25 this clamp. The side walls of this clamp are provided with cutouts 60 so that the arm may pass through the housing as well as through the passage 57 of the block 55. When the block is in the position shown in 30 Fig. 4, the arm 43 can pass through the passage 57 but when the tumblers are turned out of the set position in which the end of the bolt will rest in the notches 30 and will engage the uncut edge portions of these 35 tumbler disks, the block will be moved outwardly against the action of the spring 56 and the passage 57 will thus be moved out of registry with the recesses 60 thereby causing the arm to strike the side face of the 40 block and preventing sliding movement of the bolt. In order to permit the bolt to be locked from the inside so that even with the combination properly set, the bolt cannot be moved inwardly, there has been provided a latch pin 61 which is slidably mounted in a socket neck 62 and engaged by a spring 63 so that it will be normally held inwardly in an operative position to 45 extend into the opening 41 of the bolt. It will thus be seen that with the latching pin set in an operative position, the bolt will be 50 positively locked and cannot be moved. By drawing the locking pin outwardly and turning it so that its side pin 64 will engage the outer end of the socket 62, the pin will be held in an inoperative position thus permitting the bolt to be moved inwardly when the combination is properly set.

A socket is to be connected with the door 55 jamb. This socket which is to be secured to the door jamb and receive the bolt 33 is provided with a body portion 65 which will be connected with the door jamb by means of screws or other similar fasteners. This 60 body portion is provided with a pocket 66

and is provided with a sliding plate 67 forming an outer wall section for the pocket. An arm 68 extends from the major portion of the body in which the pocket 66 is formed and is cut to provide a tongue 69 70 which will extend into a shallow recess 70 formed in the plate 67, when this plate is moved to an open position beneath the tongue as shown in Fig. 5. A pin 71 is positioned within the interior of this arm 68 75 and carries a spring 72 which engages a tongue extension 73 which extends inwardly from the plate 67 so that ordinarily the plate will be held in the closed position. The head of this pin will however limit 80 movement of the plate under action of the spring and therefore the plate cannot move towards a closed position beyond the position shown in Fig. 1. An actuating pin 74 extends from this plate so that the plate can 85 be readily moved to an open position. It is desired to permit the plate to be releasably locked in an open or a closed position and therefore there has been provided a locking pin 75 which is slidably mounted in a neck 90 76 of the tongue 69 and engaged by a spring 77 so that the pin will be yieldably held in a position to extend through either the opening 78 or the opening 79 according to whether the plate is in a closed or an open 95 position. In order to permit the plate to be releasably held in an open position and permit it to move to a closed position when the bolt has been turned to an extended position and the door closed, there has been 100 provided a latching plate 80 which is loosely mounted in the bottom of the pocket 66 and engaged by a spring 81 which will tend to move the plate and extend the tongue 82 thereof upwardly to the position shown in 105 Fig. 7. When the plate is moved to an open position and held in this position by the pin 75, the plate will extend slightly across the end of the tongue 82 as shown in Fig. 6 and the tongue will thus be prevented from preventing closing of the plate. When however 110 it is desired to have this plate held open by the tongue of the plate, the pin 75 will be drawn outwardly and the plate moved toward an open position a small amount so 115 that it assumes the position shown in Fig. 7 with the tongue 82 extending in front of and engaging the edge of the plate. The door can then be closed with the locking bolt extended to the operative position and when 120 this locking bolt strikes the plate 80, it will move this plate inwardly and thus move the tongue 81 from in front of the plate 67. The spring will then move the plate 67 to the closed position and the door cannot be 125 unlocked until the proper combination is set to permit the bolt to be moved inwardly. When this lock is in use, the socket will be secured to the door jamb and the housing of the lock will be secured to the door with the 130

neck 4 extending through an opening formed in the door. The cup 13 can then be secured to the door and after the cup is in place, the dial put in place with the hollow shaft section carried by the dial extending inwardly with its arms extending between the arms 17. After the dial is in place, the hollow shaft 9 will be passed through the hollow sectional shafts of the permutation mechanism and the securing pin 51 put in place and secured by the screw 54. The cover plate 5 of the housing will then be put in place and secured by the screws and the lock is ready for use. When the combination is scattered, the hollow shaft 9 may be turned by means of its operating head 10 and movement will be imparted to the core and the core will have sliding movement. The block 55 will however prevent the arm 43 from passing through the bracket 58 which holds the block in place and therefore the bolt cannot move inwardly to the inoperative position. Therefore, there will be no danger of the lock being broken by forced turning of the shaft 9 with the combination scattered. In order to set the combination, the dial is turned first in one direction and then in another until the tumblers have been moved to bring the notches into alinement so that the spring can move the block 55 to bring the passage 57 into registry with the cutout 60 and permit free passage of the arm 43. In the present illustration, the dial will first be turned to the right by means of the knob 11 until the member 35 is in position with respect to the mark 83 upon the cup 13. The dial will then be rotated in the opposite direction for two revolutions to bring the number 14 into proper position with respect to the mark 83. In doing so, the screw 32 of the tumbler disk 19 will have engaged the co-operating screw 32 of the disk 20 and cause this disk 20 to rotate with the disk 19 until the second screw of this disk engages the screw 32 of the disk 21 and moves this disk 21 to the set position at 35. During the reverse movement to the point 14, the screw 32 of the disk 19 will first move out of engagement with the co-operating screw of the disk 20 and after a revolution will again engage this screw and turn the disk 20 to bring its notch into proper position with respect to the notch of the disk 21. After the disks 21 and 20 have been set, the dial will again be turned toward the right or in other words in the first direction of movement and brought to a stop at the mark 29 in which position all of the notches of the disks will be in alinement and the block 55 may move to the position of Fig. 4. With the block in this position, the arm 43 may pass through the notch 57. The head of knob 10 can then be turned to rotate the shaft 9 and the bolt 33 will be drawn inwardly and thus permit the door to be

opened. The combination can then be left in the set position so that the bolt can be moved inwardly or outwardly at will or the bolt can be moved outwardly and the combination scattered so that it will be locked in the extended position. If this is done, the plate 67 will be moved to the open position and the door can be opened or closed as long as the plate is secured in the open position. If during the day, it is desired to positively lock the door from the inside and prevent anyone from opening it from the outside, the door may be closed and the plate released so that it may move to the closed position. The locking pin 61 which would ordinarily be held in a raised or inoperative position will be turned so that it may move to a locking position and will extend down into the opening of the bolt 33 thus preventing anyone from drawing the bolt inwardly to the inoperative position even with the combination set. When leaving the room and it is desired to have the door locked, the plate will be moved to the position shown in Fig. 7 with the tongue 82 engaging the edge of the plate. The door can then be closed and when the extended bolt strikes the plate 80, the tongue will be moved inwardly out of engagement with the plate 67 and the spring 72 will move the plate to the closed position thus preventing opening of the door until the combination is again set to draw the bolt inwardly to the inoperative position. It will thus be seen that there has been provided a lock which can be securely locked and which is so constructed that the permutation locking mechanism cannot be broken by turning of the head 10 with the combination scattered. It will be further noted that a lock has been provided which is so constructed that the bolt may be very securely held in a locked position but very easily moved to an inoperative position with the proper combination set. It will be further noted that there has been provided a very efficient permutation mechanism for releasably holding the bolt in a locked position and also that there has been provided means which will permit of the bolt being locked against movement to an inoperative position even with the combination set. This latching mechanism would be very effective in locking the door against intruders where the occupant of the room did not have time to scatter the combination. It will be further noted that there has been provided an improved type of socket for use in connection with the lock, the socket being provided with mechanism depending for its operation by co-operation with the bolt of the lock mounted upon the door.

I claim:

1. A lock comprising a door engaging housing, a jamb engaging socket including a wall section movable to an open position and

yieldably held in a closed position, latch means for releasably holding the wall section in an open position, a bolt carried by the door engaging housing and movable into and out of an operative position, means for releasably locking the bolt in an operative position for passing into the socket and engaging said latch to move the latch to an inoperative position and permit movement of the wall section to a closed position, and additional means for engaging the movable wall section and releasably holding the movable wall section in an open position.

2. The structure of claim 1 having the movable wall section when engaged by the last mentioned securing means extending across and rendering the first mentioned latch means inoperative.

3. A lock comprising a door jamb engaging socket having a wall section slidably mounted for movement into and out of a closed position, resilient means yieldably holding the wall section in a closed position, latching means within the socket yieldably held in position to engage the wall section and hold the same in an open position, a door engaging housing, a bolt movable into and out of the housing, locking means in the housing for locking the plunger in an extended position for entering said socket when a door is closed and engaging the latching means therein to move the same and release the wall section to permit the wall section to move to a closed position and prevent movement of the bolt out of the socket while locked in an extended position, and additional means for locking the wall section in an open position and preventing its movement to a closed position, the last mentioned locking means further serving as means for locking the wall section in a closed position.

4. A lock comprising a housing, a bolt carried by the housing for sliding movement into and out of an operative extended position, a core slidably mounted in the bolt and having frictional binding engagement with the bolt, operating means having connection with said core for moving the core and thereby imparting movement to the bolt, and means for locking the bolt in an extended position, the core being permitted of movement when the bolt is locked.

5. A lock comprising a housing, a bolt slidably carried by the housing for movement into and out of an operative position, means for releasably locking the bolt in an operative position, a core slidably mounted in the bolt and having frictional engagement with the bolt permitting movement of the core independent of the bolt when the plunger is locked in an operative position, and means for imparting movement to the core.

6. The structure of claim 5, having the core slidably mounted in a pocket of the

bolt and provided with a transversely extending passage, a spring in the passage and gripping balls in the ends of the passage engaged by the spring and held in tight engagement with the walls of the pocket, the walls of the pocket being provided with recesses receiving the balls to frictionally lock the core against movement in the pocket of the bolt.

7. The structure of claim 5, having the means for imparting movement to the core consisting of a rotatable shaft, an eccentric ring carried by said shaft, and a band fitting upon said ring and having a radially extending ear pivotally connected with the core whereby rotation of the shaft in either direction will impart sliding movement to the core and bolt.

8. The structure of claim 5, having the bolt provided with side arms extending longitudinally of the housing, one of the arms having a finger extension fitting into a groove in the housing and the second having a slot receiving a pin for limiting and guiding sliding movement of the bolt, the locking means engaging one of the arms to hold the bolt against sliding movement.

9. The structure of claim 5, having the bolt provided with side arms guiding and limiting sliding movement of the bolt, the locking means for the bolt consisting of a slidably mounted block spring held in position to permit movement of the plunger through engagement of the block by one of the arms of the bolt, and means for moving the block into a position for blocking movement of the bolt inwardly to an inoperative position.

10. The structure of claim 5, having the bolt provided with side arms guiding and limiting sliding movement of the bolt, the locking means for the bolt consisting of a slidably mounted block spring held in position to permit movement of the bolt through engagement of the block by one of the arms of the bolt, a rotatable setting shaft, and tumbler disks carried by the shaft and having their peripheral edges engaging the block to hold the block in a position blocking movement of the bolt arm, the disks being provided with notches permitting movement of the block to an arm releasing position when the notches are in alinement.

11. A lock comprising a housing, a bolt slidably into and out of the housing, means for locking the bolt in an extended position comprising a sliding block blocking inward movement of the bolt when moved out of a normal position, a hollow shaft extending into the housing and having outer and inner end sections provided with interlocking arms, a dial and turning head carried by the outer section, a tumbler disk rigid with the inner section, other disks loose

upon the inner section, abutment pins fitting into selected openings in the disks and engaging to set the disks in position permitting movement of the block to an inoperative position when the shaft is rotated to predetermined positions with respect to the dial, a rotatable bolt operating shaft ex-

tending through the hollow shaft, an eccentric disk upon the last mentioned shaft, and a band fitting loosely upon the disk and having pivotal connection with the bolt.

In testimony whereof I have hereunto set my hand.

FRANK DI BELLA.
